(57) **CLAIM**

The ornamental design for a traveler mug, as shown and described.

DESCRIPTION

FIG. 1 is a top right perspective view of a traveler mug showing my new design.

FIG. 2 is a front elevational view of the design.

FIG. 3 is a right side elevational view of the design.

FIG. 4 is a rear elevational view of the design.

FIG. 5 is a left side elevational view of the design.

FIG. 6 is an enlarged, partial sectional view of the encircled area in FIG. 5 illustrating the partially transparent nature of an outer shell of the design;

FIG. 7 is a top plan view of the design;

FIG. 8 is a bottom plan view of the design;

FIG. 9 is a top right perspective view showing a second embodiment of my new design;

FIG. 10 is a front elevational view thereof;

FIG. 11 is a right side elevational view thereof;

FIG. 12 is a rear elevational view thereof;

FIG. 13 is a left side elevational view thereof;

FIG. 14 is an enlarged, partial sectional view of the encircled area in FIG. 12 illustrating the partially transparent nature of an outer shell of the second embodiment of the design;

FIG. 15 is a top plan view thereof; and,

FIG. 16 is a bottom plan view thereof.

CERTIFICATE OF CORRECTION

PATENT NO. : Des. 469,309 S
DATED : January 28, 2003
INVENTOR(S) : Gregory T. Janky

Page 1 of 5

It is certified that error appears in the above-identified patent and that said Letters Patent is hereby corrected as shown below:

Drawings.

The attached drawings that are correctly numbered Figures 5 through 16 should be substituted for the previous drawings in accordance with the description of the drawings in the patent, so that Figure 5A is renumbered as Figure 6; Figure 6 is renumbered as Figure 7; Figure 7 is renumbered as Figure 8; Figure 8 is renumbered as Figure 9; Figure 9 is renumbered as Figure 10; Figure 10 is renumbered as Figure 11; Figure 11 is renumbered as Figure 12; Figure 12 is renumbered as Figure 13; Figure 14 is renumbered as Figure 15 and Figure 15 is renumbered as Figure 16, and so that Figure 14 (previously numbered as Figure 12A) is added.

Figure 14 (previously numbered as Figure 12A) should be added.
